Emil C. Nebel, Westport, Conn., assignor to Dorr-Oliver Incorporated, Stamford, Conn., a corporation of Delaware

Application January 20, 1955, Serial No. 483,049

16 Claims. (Cl. 209—159)

This invention relates to the hydraulic classification treatment of pulps containing a range of particle sizes from fine to coarse, as exemplified by metallurgical pulps or pulps of wet-ground ore, whereby the particles of the mixture are classified into a coarse and a fine fraction of sizes, herein also termed the coarse fraction and the fines fraction, or else the oversize and the undersize respectively. The coarse fraction will contain substantially all particle sizes below, and the fines fraction substantially all sizes above the so-called "cut" or point of fractionation.

A well known application of such two fraction classifiers lies in the field of continuous closed circuit grinding of metallurgical pulps where the classifier operates in circuit with a wet grinding mill, and in which the mill delivers to the classifier a pulp containing particles ranging from fine to coarse, and the classifier produces a coarse particle fraction to join fresh pulp feed for return to the mill to be further comminuted while the fraction of fine particles leaving the classifier is being eliminated from the circuit.

Hydraulic separation of particle sizes as herein contemplated takes place in a pool to which the pulp is fed while the coarse fraction is withdrawn from the bottom of the pool and the fines fraction overflows from the pool across a weir. The mixture of particle sizes while in transit through this pool is kept mobilized or in a state of teeter by being subjected to the effect of upward flow of auxiliary so-called hydraulic operating water rising from the bottom of the pool at a controlled velocity or rate. In this way, a desired coarse fraction above a certain mesh size will collect at the bottom of the pool to be withdrawn therefrom, while a corresponding fraction of fine sizes with its carrier water overflows from the pool. In such classification apparatus it is important that controls be provided whereby the point of fractionation or "cut" between the oversize and the undersize can be readily established and accurately adjusted. For example, if the feed be of a run containing particle sizes ranging, say, from 28 to 200 mesh, then it should be possible, for example, to make a clean split at say 100 mesh, yet it should be possible to readily shift the "cut" to, say 48 mesh. This calls for providing simple and effective means for so adjusting or shifting the "cut" while deriving the respective size fractions clean, that is with a minimum of stray sizes admixed thereto. For example, the importance of producing a clean coarse fraction is apparent where the classification apparatus operates in closed circuit with a wet grinding mill, the mill to receive coarse fraction particles for regrinding, and where the admixture of an appreciable amount of undersize or stray sizes would burden the circulating load through the mill and would accordingly reduce its efficiency as well as that of the circuit as a whole.

Another problem is that such apparatus should be capable of handling effectively a feed slurry or pulp

containing a relatively wide range of particles from relatively very fine to relatively very coarse.

Other problems encountered are to derive the overflow of the fines at the highest possible density, or else 5 to operate with a minimum of operating water required, even though relatively very coarse particles at the bottom of the pool must be induced to migrate towards the underflow discharge.

In view of these problems, it should be understood that 10 when operating under the desired upflow classification and teeter conditions there are established and maintained in the pool a coarse solids zone at the bottom, a fines zone at the top, and an intermediate teeter zone of mixed particles of both fractions. The fines fraction 15 is delivered by overflow from the top zone. The coarse particle fraction is allowed to discharge from the bottom zone at a rate which is automatically controlled in response to density variations in the teeter bed of the pool, in such a manner that a lowering of the pulp density 20 below a desired value is at once corrected by a restraining or throttling of the coarse fraction discharge, while a rise in pulp density above the desired value is corrected by increasing the rate of coarse fraction discharge.

In other words, the coarse fraction discharge is thus 25 automatically controlled to maintain a substantially constant pulp density in the teeter bed, thereby in turn maintaining a desired "cut" defining the point of size fractionation. For example, in the patent to W. C. Weber No. 2,320,588 such coarse fraction control is accomplished automatically by way of allowing the coarse material from the bottom zone to migrate through a passage at the bottom and by way of a so-called sands seal over a submerged weir into a clear-water chamber representing a clear water column maintained in hydraulic balance 30 with the pulp column as represented by the effective depth of the pool.

Another mode of coarse fraction discharge control is 35 by way of controlling spigot discharge directly from the coarse fraction bottom zone of the pool.

40 In order to attain the above mentioned objects, this invention provides classification apparatus in which pulp of mixed particle sizes is fed to the pool while hydraulic operating water is introduced at the bottom of the pool in such a manner and at such a rate that the above defined classification zones and teeter conditions are thereby substantially maintainable. In addition to a basic upflow rate of the operating water or superimposed thereon, this invention proposes to apply to the pulp bed in the pool upflow pulsations of such frequency, intensity and volume, 45 that the largest particles at the bottom of the coarse fraction zone will thereby be caused or be induced to migrate along the bottom to the point of discharge.

In other words, the pulse effect of this machine is produced by a separate hydraulic system acting on the upflowing stream of teeter water passing through a false bottom in the form of a screen or constriction plate.

According to one embodiment, the pool is defined by a tank structure which has a false bottom in the form of a constriction plate having above it the classification pool proper and below it a water supply chamber. Hydraulic water is fed at a controlled rate to the supply chamber from which the water upflows through the constriction plate at a rate to sustain the desired teeter condition in the pool. Pulsations are imposed upon the body of operating water in the supply chamber, as by means of a pulsating valve through which secondary operating water is admitted to the chamber interruptedly in the form of pulsations of suitable characteristics, or else the pulsations are imparted by the rapid pumping or liquid discharge effect of a mechanically actuated diaphragm. According to one form, discharging of coarse fraction particles is into a receiving chamber representing a clear

water column in hydraulic balance with the pulp column as represented by the effective depth of pulp in the pool. According to another form, the tank structure has the pool above and the water supply chamber below the constriction plate while the coarse fraction material is spigoted directly from the bottom zone of the pool. A density-responsive control device adjusts the spigot discharge valve automatically in a manner whereby pulp density in the pool is maintained substantially constant at a desired value, so that in turn a desired "cut" or point of fractionation may thereby be maintained.

Another embodiment presents a tank structure without constriction plate, and without the water supply chamber therebeneath, in that it provides jet-emitting water supply conduits extending from an overhead supply downwardly into proximity of a solid tank bottom. Pulsations are imposed upon the steady supply of operating water in this supply conduit system. Discharge of coarse fraction material is from the bottom zone of the pool directly through a spigot discharge valve which is automatically settable by means of a control device responsive to pulp density changes in the pool.

Still another embodiment presents a tank structure in which a false bottom in the form of a constriction plate is vertically vibratable between the body of pulp above and the body of operating water below. A main supply of operating water enters a chamber below the constriction plate to rise therethrough at a steady rate for maintaining the classification zones or teeter condition in the pool as above defined, while the vertical vibrations of the constriction plate serve to provide the additional inducement hydraulically for the coarsest particles in the bottom zone to migrate towards discharge. Coarse fraction material discharges through a submerged passage, through a sands seal and over a submerged weir into a receiving chamber representing a clear water column in hydraulic balance with the pulp column as represented by the effective depth of the pool or the effective specific gravity thereof.

According to one feature, two pulse effects are applied in combination in such a manner that the impact curve of the compound effect of these effects upon the teeter bed may be rendered more nearly in the form of a sine curve instead of as a square curve. In this way there is attainable a pulsation impact curve better suited for the kind of classification operation contemplated by this invention.

In summary, this invention provides a classification machine in which pulse effect is added to the flow of teeter water upflowing through the pool of pulp undergoing classification treatment, while the rate of discharge of coarse fraction material from the bottom zone of the pool is automatically controlled in response to pulp density changes in the pool, in a manner whereby the pulp density is kept substantially constant, and thereby the "cut" or point of particle size fraction is maintained at a desired value.

As this invention may be embodied in several forms without departing from the spirit or essential characteristics thereof, the present embodiment is therefore illustrative and not restrictive, since the scope of the invention is defined by the appended claims rather than by the description preceding them, and all changes that fall within the metes and bounds of the claims, or of forms that are their functional as well as conjointly cooperative equivalents are therefore intended to be embraced by those claims.

In the drawings:

Figure 1 shows the invention embodied in a tank structure of the constriction plate type with coarse fraction discharge over a weir into a receiving chamber, with pulsations supplied by a pulsating water supply valve, and coarse fraction discharge control by means of controlled hydraulic balance of the clear water column in the receiving chamber as against the pulp column in the pool.

Figure 2 shows the machine substantially resembling that of Figure 1, except for the fact that the pulsations are membrane-induced.

Figure 3 shows an embodiment of the machine differing from the Figure 1 and 2 embodiment by the provision of direct spigot discharge of the coarse fraction material, and of corresponding pulp density responsive discharge control devices.

Figure 4 shows one embodiment of the machine differing from the Figure 1 and 2 embodiment by the provision of overhead supply of operating water to the solid tank bottom, while employing the Figure 3 provision of direct spigot discharge of coarse fraction material from the bottom zone of the pool with pulp density responsive automatic control devices for the spigot discharge.

Figure 5 is a cross-sectional view taken on line 5—5 of Figure 4.

Figure 6 shows an embodiment of the machine, which differs from the preceding embodiments by employing a constriction plate which is vertically reciprocable or vibratable between the pool of pulp and the water supply chamber.

The machine of the Figure 1 embodiment is represented by a tank structure for instance, round or square in cross section, comprising an outer wall structure 10 having a conical or hopper-shaped bottom portion 11; an inner wall structure 12 which is upwardly and downwardly open-ended and has fixed relationship with respect to the surrounding outer wall structure 10; and a supply chamber 13 for operating water disposed substantially within or surrounded by the hopper-shaped bottom portion 11, and comprising a horizontal top plate in the form of a constriction plate 14, a vertical wall portion 15, and a hopper-shaped bottom portion 16. The inner wall structure 12 is fixedly connected with and supported by the outer wall structure 10 by means of a cover plate 17 defining above it an overflow launder 18 for receiving and discharging the overflowing fines fraction, and below it a receiving chamber 19 into which the coarse fraction particles will discharge. That is to say, the inner wall structure 12 together with constriction plate 14 defines a pool of pulp "P" undergoing classification treatment while the outer tank wall structure 10 with hopper-shaped bottom 11 and cover plate 17 defines the receiving chamber 19 surrounding the pool "P" as well as the water supply chamber 13.

The vertical wall portion 15 of water supply chamber 13 rises a distance h_1 sufficiently above the constriction plate 14 to constitute a submerged discharge weir 20 to surround the lower free end of the inner wall structure 12 in horizontally spaced relationship therewith. The lower end of inner wall structure 12 in turn is spaced a distance h_2 upwardly from the constriction plate 14 to constitute therewith a coarse fraction discharge passage 21, there being provided a slight vertical overlap "O" between the submerged weir 20 and the lower end of the inner wall structure 12, constituting what is herein termed a sands seal effective between the pool "P" and the body of water in the receiving chamber 19. The structure 60 which constitutes the water supply chamber 13 is supported upon the outer wall structure as by brackets 13a which may be adjustable if desired so that the height of passage 21 may thereby be rendered adjustable.

A supply pipe 22 penetrating the outer as well as the inner wall structures, leads into the water supply chamber 13 for supplying operating water thereto. The pipe 22 in turn receives a steady or uniform flow of pressure water from a first branch pipe 23 provided with control valve 24. A second branch pipe 25 provides a pulsating flow of operating water to enter the supply pipe 22 by way of a pulsator device 26 which of itself is well known.

The introduction of feed pulp into the pool "P" is indicated by a feed pulp inlet pipe 27, while a discharge conduit 28 indicates the passage of the overflowing fines fraction from the launder 18 and a bottom outlet 29 provided

with control valve 30 indicates the discharge of coarse fraction material from the hopper-shaped bottom 11 of the receiving chamber 19. The outer tank structure 10 has an upward stack-like extension 31 laterally disposed to accommodate a clear water column 32 the top level "L₁" of which is defined by an overflow pipe 33 comprising a stack of removable rings 34 for adjusting the super-elevation "S" of clear water level "L₁" and the top level "L₂" of the pool of pulp.

A so-called hutch discharge connection is provided in the form of a pipe 35 leading from the bottom of the water supply chamber 13 extending through an opening in the hopper-shaped bottom 11. That is to say, any fine particles of pulp that may find their way from the pulp bed or pool of pulp downwardly through the constriction plate 14 may be discharged from the water supply chamber 13 through pipe 35 by way of a valve 36 provided in the pipe. The pipe 35 while connected rigidly with the supply chamber 13 is sealed off against the wall of bottom 11 by means of a conically shaped rubber sleeve 37 having a narrower outer end 38 surrounding and hugging pipe 35 and sealingly fastened thereto, and having a flanged end 39 sealingly fastened to the inclined wall of bottom 11. The pulsator device 26 of known construction comprises an annular chamber 40 concentric with and fastened to branch supply pipe 25, formed by a shallow casing 41 having mounted thereon conically shaped valve seat member 42 upon which closes a spring-loaded valve member 43 movably connected to the outer flanged end portion 41^a of casing 41 by means of a diaphragm member "M." Spring pressure is exerted upon the valve member 43 by a compression coil spring 44 confined between the valve member 43 and a yoke structure 45 rigidly fastened upon the flanged end portion 41^a of casing 41. The spring loading upon the valve member is adjustable as indicated by a screw spindle 46 with lock nut 47. The annular chamber 40 has a supply pipe 48 for supplying pressure water thereto.

The pulsator device 26 functions to convert the steady water pressure supplied by pipe 48 into pressure pulsations reaching the body of water in the supply chamber 13 and superimposes the water pressure of the steady or uniform water supply entering the chamber 13 from branch pipe 23.

That is to say, the continuous water pressure from supply pipe 48 acting upon the diaphragm "M" lifts the valve member off its seat 42 sufficiently to allow the supply pressure to drop momentarily as the water surges past the valve into pipe 22 and into chamber 13. This momentary pressure drop again allows the valve to close, so that the normal water pressure from pipe 48 will restore itself to the point of again lifting the valve member 43. The frequency and character of these pressure pulsations can be adjusted by way of adjusting the pressure of spring 44.

The operation of the Figure 1 embodiment of the machine is as follows:

While pulp of a suitable concentration containing a range of particle sizes from fines to coarse, is being supplied continuously to the pool "P" from feed pipe 27, operating water continuously enters the chamber 13 below the constriction plate 14 at a rate great enough to maintain the material in the pool "P" in a teeter condition suitable for effecting the desired classification.

That is to say, hydraulic upflow or hindered settling conditions are thus maintained whereby there are established in the pool substantially three classification zones, namely a bottom zone "a" of coarse particles for underflow discharge from the pool, a top zone "b" of fines to overflow from the pool, and an intermediate or teeter zone "c" of mixed particle sizes in teeter condition.

The pulsations which are superimposed upon the uniform rate of water supply into the supply chamber 13 have the effect of maintaining the layer of coarse fraction particles closest to the constriction plate in a state of

fluidity enabling them to migrate towards and through the discharge passage 21, so that these coarse fraction particles will then pass through the sands seal represented by the overlap "o" and spill across the submerged weir 20 into the receiving chamber 19.

With the pulp in the pool thus maintained in a fluid or teeter condition, control of the fractionation point or "cut" is here affected by way of balancing the height of the pulp column H₁ in the pool defined by overflow level L₂, against the height of a clear water column H₂ defined by overflow level L₁. That is to say, by adjusting the clear water overflow level L₁ upwardly the fractionation point can be shifted towards the coarse particle end of the size range, whereas adjusting the overflow level L₁ downwardly will move the fraction point towards the fine particle end of the range.

However, by maintaining the clear water overflow at a chosen level L₁ the average density of the pulp in the teeter bed of the pool is maintainable at a constant value, which in turn maintains the fractionation or "cut" substantially constant at a desired point. Fine particles which may find their way downwardly through the constriction plate 14, will collect at the bottom of supply chamber 13 whence they can be withdrawn periodically by way of manipulating the valve 36 of the hutch discharge pipe 35.

The Figure 2 embodiment is similar to the Figure 1 embodiment in its general structural organization, but differs with respect to the addition of pulsation inducing means in the form of liquid displacing means such as diaphragm means associated with the water supply chamber 13 and reciprocatory actuating means therefor.

Hence, the tank structure of the Figure 2 embodiment comprises an outer wall structure 49 having a conical or hopper-shaped bottom portion 50; an inner wall structure 51 which is upwardly and downwardly open-ended and has fixed relationship with respect to the surrounding outer wall structure 49, and a supply chamber 52 for hydraulic operating water and disposed substantially within or surrounded by the bottom portion 50, and which supply chamber comprises a horizontal top plate in the form of a constriction plate 53, a vertical wall portion 54, and a conical hopper shaped bottom portion 55.

The conical portion comprises a top section 55^a and bottom section 55^b both fixedly mounted with respect to the surrounding tank structure, and an intermediate section 55^c connected to the top section 55^a and the bottom section 55^b by means of correspondingly shaped conical membranes 55^d and 55^e respectively.

Up and down reciprocation or vibration is imparted to the intermediate conical bottom section 55^c by means of actuating mechanism here shown to comprise a pair of vertical actuating rods 55^f and 55^g extending from the section 55^c downwardly through the hopper-shaped bottom 50 in liquid-sealing relationship therewith. The lower ends of the actuating rods 55^f and 55^g are interconnected by means of a yoke member 55^h to which the up and down movement is imparted by an eccentric device 55ⁱ driven by a motor 55^k. Sealing relationship between the actuating rods 55^f and 55^g and the tank bottom 50 is established by means of rubber jackets 55^l and 55^m having their upper ends sealingly connected to the tank bottom and their lower ends sealingly connected to the respective actuating rods.

The inner wall structure is fixedly connected with and supported by the outer wall structure 49 by means of a coverplate 56 defining above it an overflow launder 57 for discharging the fines fraction, and below it a receiving chamber 58 into which the coarse fraction particles will discharge.

That is to say, the inner wall structure 51 together with constriction plate 53 defines a pool of pulp "P₁" undergoing classification treatment, while the outer tank wall structure 49 with hopper-shaped bottom portion 50 and

cover plate 56 defines the receiving chamber 58 surrounding the pool "P₁" as well as the water supply chamber 52.

The vertical wall portion 54 of supply chamber 52 rises a distance "*h*₃" above the constriction plate 53 to constitute a submerged discharge weir 59 to surround the lower free end of the inner wall structure 51 in horizontally spaced relationship therewith. The lower end of inner wall structure 51 in turn is spaced a distance "*h*₄" upwardly from the constriction plate 53 to constitute therewith a coarse fraction discharge passage 60, there being provided a slight vertical overlap "*o*₁" between the submerged weir 59 and the lower end of inner wall structure 51, constituting what is herein termed a sands seal effective between pool "P₁" and the body of water in the receiving chamber 52. The structure which constitutes the water supply chamber 52 is supported upon the outer wall structure as by bracket 52^a which may be adjustable if desired so that the height of discharge passage 60 may thereby be rendered adjustable.

A supply pipe 61 penetrating the outer as well as the inner wall structure, leads into the water supply chamber 52 for supplying operating water thereto. The pipe 61 in turn receives a steady or uniform flow of pressure water from a first branch pipe 62 provided with control valve 63. A second branch pipe 64 provides a pulsating flow of operating water to enter the supply pipe 61 by way of a pulsator device (not shown) which may be similar to that shown and described in connection with the Figure 1 embodiment.

The introduction of feed pulp into the pool "P₁" is indicated by a feed pulp inlet pipe 65, while a discharge conduit 66 indicates the passage of the overflowing fines fraction from the launder 57 and a bottom outlet 67 with control valve 68 indicates the discharge of coarse fraction material from the hopper-shaped bottom portion 50 of the receiving chamber 58.

The outer tank structure 49 has an upward stack-like extension 69 laterally disposed to accommodate a clear water column 70 the top level "T" of which is defined by an overflow pipe 71 comprising a stack of removable rings 72 for adjusting the super-elevation "Q" of clear water level "T" over the top level "R" of the pool of pulp "P₁".

The so-called hutch discharge connection is provided in the form of a pipe 73 leading from the bottom of the water supply chamber 52 extending through an opening in bottom portion 50 of the outer tank structure, the pipe 73 being fixedly connected to the sloping wall of the tank bottom as by means of a flange 74 welded to pipe 73. That is to say, any fine particles that may find their way from the pulp bed or pool of pulp downwardly through the constriction plate 53, may be discharged from the water supply chamber 52 by way of manipulating a valve 73^a provided in the pipe. The compound effect of the two pulsation inducing devices in this embodiment makes it possible to modify pulsation characteristics in the shape of the pulsating curve.

The operation of the machine according to the Figure 2 embodiment of the machine is substantially similar to that described above in connection with the Figure 1 embodiment. That is to say, the rate of supply of operating water is controlled in such a manner that in the classifier pool there are established a bottom zone *a'* comprising coarse fraction solids for underflow discharge from the pool, a top zone *b'* comprising the fines to overflow from the pool, and an intermediate zone *c'* comprising a mixture of the particle sizes in teeter condition.

The pulp density and fractionation control of the classifier pool of Figure 2 is by means of the clear water balancing column 70 similar to the Figure 1 embodiment. But the characteristics of the pulsations can be influenced or the pulsation curve be shaped additionally because of the pulsations which are due to the up and down reciprocations of the bottom section 55^c in addition to the pulsating flow of operating water from branch pipe 64.

The Figure 3 embodiment differs from the preceding embodiment mainly in that it provides discharge for the coarse fraction particles through a controlled discharge area or valve, directly from the sands zone at the bottom 5 of the pool. Control devices are provided for automatically adjusting the discharge valve or discharge area in response to density changes in the teeter bed or pool, so that the pulp density and thereby the point of fractionation or "cut" is kept substantially constant.

10 The machine of the Figure 3 embodiment is represented by a tank structure 74 which comprises a top portion 75 of the height *S*₁ containing the pulp bath proper and a hopper-shaped bottom portion 76 of the height *S*₂ defined against the top portion 75 by a false bottom constriction plate 77. The upper tank portion 75 has a feed inlet chute 78 at one end, and an overflow weir 79 for the fines at the opposite end for the fines fraction to pass into an overflow launder 80 having a discharge connection 81. The hopper-shaped bottom portion 76 represents a water

15 supply chamber 82 having a pressure water supply connection 83 into which feed a pair of branch connections 84 and 85, the branch connection 84 to supply a steady flow of operating water, the branch connection 85 to supply a pulsating flow of operating water, as by means of a pulsating device or pulsator similar to the one in the Figure 1 embodiment but here not shown. Control and shut-off valves for the branch pipes 84 and 85 are indicated at 84^a and 85^a respectively. Additional pulsating means are provided in the form of a diaphragm

20 pumping or pulsating device 86 comprising a plunger member or plate member 87 constituting a portion of the hopper shaped bottom 76 and movably connected thereto by means of an annular diaphragm member 88. Drive means 89 are shown for reciprocating or vibrating the plunger plate 87. Fine particles which may enter the supply chamber 82 downwardly through the constriction plate 77 will collect at the bottom of supply chamber 82 whence they can be withdrawn periodically by the manipulation of a hutch discharge valve 82^a.

25 The upper tank portion 75 is of the length "*l*₁" comprising the length "*l*₂" of the constriction plate proper plus an overhanging length "*l*₃" extending beyond the hopper-shaped bottom portion 76 of the tank structure. The overhanging tank portion has a flat solid bottom 89 extending from the outer end of the constriction plate 77, and provided with a spigot discharge connection 90 for the discharge of coarse fraction particles from the pool through a hand-operated shut-off valve 91. Automatic control is accomplished by means of an air pressure controlled rubber spigot valve "V," having an inflatable rubber annulus *N* representing the variable throughflow area of spigot valve *V*. Density responsive control devices in the form of a relay system *E* are provided for automatically adjusting the throughflow area of spigot valve *V* in a manner to maintain substantially constant the density of the teeter bed and thus the point of size separation or fractionation between the underflow and the overflow particles.

30 The automatic control system "E" for the spigot valve "V" comprises a clear water balancing column 92 provided with make-up water supply 92^a, which column communicates with the teeter bed of the pool, and a relay system *R* operatively interconnecting the balancing column 92 with the spigot valve *V* so that variations in the height of the balancing column, reflecting variations in density of the teeter bed, will correctively adjust the opening or throughflow area of spigot valve *V*.

35 This control system, therefore, may be regarded as comprising a pressure control which senses and responds to changes in the height of the superelevation of the balancing column in pipe 92 over the height of the pulp column in the pool. This pressure control varies air pressure actuating a booster relay system which in turn regulates the air pressure controlling the diameter or throughflow area of the rubber spigot valve *V*.

The underflow discharge control system thus comprises the stationary open-ended vertical pipe 92 the lower end of which extends a suitable distance into the teeter feed of the pool of pulp undergoing classification in the tank. If the superelevation of the clear water in pipe 92 should rise, the relay system will act to increase the throughflow area of the spigot valve so as to allow an increased volume of pulp to discharge until the superelevation in pipe 92 is restored to its normal predetermined level, at which time the spigot valve "V" will again constrict to a diameter to hold the superelevation level correspondingly. Conversely, if the superelevation in pipe 92 should decrease, the spigot valve "V" will constrict sufficiently to reduce the throughflow volume of underflow pulp leaving the machine, thus in turn returning the height of superelevation in pipe 92 to the normal level.

This relay control system R comprises a master control 93 having pressure communication 93^a with the superelevation pipe 92, which master control device responds to changes in the height of the water column of superelevation in pipe 92, and is adapted to control the application of relay air pressure to the spigot valve "V". The master control unit 93 is here shown to be in the form of a Minneapolis Honeywell Pressure Control Type P097A. In that device a bellows 94 communicates with the superelevation pipe 92 which in turn communicates with the teeter bed of the classifier pool. Any change in the height of the water column in the pipe 92 manifests itself by an expansion or contraction of the bellows 94 of pressure control unit 93, which expansion or contraction of the bellows actuates a lever 95 to swing about the fixed knife edges 96 and 97. The motion of lever 95 is transmitted through linkage 98 to a flapper valve 99 the lowering or raising of which regulates the amount of air allowed to escape from an air nozzle 100.

A supply of high pressure air entering the relay control system is indicated at 101 passing through a constant pressure regulating valve "C." This pressure is reduced by a constriction or adjustable orifice such as provided by an adjustable needle valve unit 102 through which the air passes into a branch pipe connection 103 leading to the air nozzle 100 of pressure control unit 93, as well as into a branch connection 103^a leading to the inflatable rubber annulus N of spigot discharge valve "V."

The pressure reduction through the needle valve 102 is such as to provide the appropriate operating pressure for the pressure control unit 93 and for the spigot valve "V" relative to the static pressure of the pulp column in the classifying pool. A pressure gauge 101^a indicates the air pressure entering at the high pressure side of the needle valve 102. A pressure gauge 101^b indicates the pressure at the low pressure side of the needle valve 101.

In the operation of this control system when the superelevation in pipe 92 rises due to an increase in pulp density of the teeter bed, such increase will expand the bellows 94 accordingly, thereby through lever 95 and link 98 raising the flapper valve 99 off the air nozzle 100 sufficiently to reduce the air pressure in the rubber spigot valve "V," thus increasing the throughflow area thereof until equilibrium or the status quo is restored in terms of pulp density in the pool and height of superelevation in pipe 92. Conversely, when the superelevation in pipe 92 should drop due to a decrease in pulp density in the pool, such decrease will contract the bellows 94 accordingly, thereby through lever 95 and link 98 lowering the flapper valve 99 towards the air nozzle 100 sufficiently decreasing the throughflow area thereof until equilibrium or the status quo is restored in terms of pulp density in the pool and height of superelevation in pipe 92.

In the operation of the machine according to the Figure 3 embodiment, the application of operating water to the supply chamber 82 is substantially similar to that described for the Figure 2 embodiment, in that it includes the combination of a pulsating flow of operating water from branch pipe 85 with membrane-induced pulsations

which are due to the reciprocations or vibration of the plate member 87, these combined pulsations being added to the uniform supply of operating water entering the supply chamber 82 from branch pipe 84. However, the classification conditions to be maintained in the classifier pool proper are similar to those to be maintained in the embodiments of Figures 1 and 2, in that the supply of operating water including uniform supply plus pulsating flow as well as extra membrane induced pulsations is so controlled as to maintain in the classifier pool substantially a bottom zone "m" of coarse fraction particles for underflow discharge from the pool, a top zone "n" of fines to overflow from the pool and an intermediate zone "o" containing a mixture of particle size in teeter condition.

In accordance with this formation of zones "m," "n," "o," the average density in the teeter bed of the classifier pool and hence the point of fractionation are maintained substantially constant automatically by the operation of the control system E described above regulating the rate of underflow discharge through spigot discharge valve "V" in response to density changes in the teeter bed of the classifier pool.

The Figure 4 embodiment differs from any of the preceding embodiments by employing overhead conduit means for the introduction of operating water into the classifier pool.

This machine comprises a tank 104 having a solid bottom 105 and side walls 106. The fines fraction overflows by way of a weir 107 as represented by the top edge of the tank. The upper portion of the tank is surrounded by an overflow launder 108 receiving the fines overflow from weir 107 and having a discharge connection 109. Operating water is supplied to the bottom strata of the classifier pool by means of a supply conduit system D which comprises a horizontally extending supply header 110 which in turn has a supply pipe 111 feeding it. Vertical branch pipes 112 extend downwardly from the header, each branch pipe 112 having a nozzle head 113 to emit jets of operating water downwardly at a suitable angle "g" towards the tank bottom, the nozzle heads 113 accordingly being spaced relatively close to the tank bottom, namely a suitable distance "d" therefrom.

Operating water is supplied to the nozzle heads 113 from a source of uniform pressure through a branch pipe 115 provided with control valve 115^a and from a source of pulsating pressure through a branch pipe 116 provided with a pulsating device or pulsator 117 similar to the one described in connection with the Figure 1 embodiment, and also having a control valve 116^a.

The introduction of pulp into the tank is indicated by a feed pipe 118, while the underflow discharge of coarse fraction from the tank is by a spigot discharge connection 119 leading directly from the bottom of the tank and provided with a manually-operable valve 120.

The rate of underflow discharge itself and thus the point of fractionation is controlled by a spigot discharge valve 121 (similar to that of the Figure 3 embodiment) having an inflatable annulus 122 whereby the throughflow area of the valve can be varied in response to density variations in the classifier pool. Automatic control of the spigot valve 121 is effected by means of a control system E' similar to that described in the Figure 3 embodiment. That is, the changes in the clear water superelevation in a density sensing pipe 123 is relayed to spigot valve 122 through the medium of auxiliary air pressure controlled by a master control unit or relay pressure control unit 124 (similar to the unit 93 in Figure 3) to govern the pressure in the inflatable annulus 122 at the low pressure side of an orifice or needle valve unit 124 (similar to unit 102 of Figure 1) supplied by a pipe 125 carrying high pressure air thereto. A constant pressure control valve 126 is provided in pipe 125 as well as an air pressure gauge 127. A make-up water clear water supply is indicated at 123^a for the clear water balancing column in pipe 123. Another air pressure gauge 128 indi-

11

cates the pressure in annulus 122 of the rubber spigot valve 121.

In the operation of the machine according to the Figure 4 embodiment, the application of the operating water to the classifier pool is again controlled in such a manner as to maintain in the pool substantially a bottom zone "p" comprising coarse fraction particles for underflow discharge from the pool, a top zone "g" of fines to overflow from the pool, and an intermediate zone "r" containing a mixture of particle sizes in teeter condition. The operating water applied comprises the uniform flow from branch pipe 115 combined with the pulsating flow from branch pipe 116 and pulsator 117. The operating water issuing from the nozzle heads 113 in the form of jets is directed at a suitable angle towards the tank bottom. As a result there rises from the bottom what is in effect an upward flow of water uniformly distributed over the tank bottom, with the pulsation adequate to maintain the coarse fraction particles at the bottom in a state of fluidity so they will migrate towards the point of underflow discharge, namely towards and into underflow discharge pipe 119.

The point of size fractionation is controlled and maintained by automatically controlling the rate of underflow discharging through rubber spigot valve 122, such automatic control being affected by the control system E' in the manner described in detail above for the Figure 3 embodiment of the machine. That control system responds to density changes in the teeter bed of the classifier pool, and applies correspondingly varying relay air pressure to the inflatable rubber annulus 122 of spigot valve 121, in that changes in the clear water superelevation in pipe 123 causes the control unit 124 to correspondingly vary the relay air pressure admitted to the rubber spigot valve "V" through needle valve 124a.

The Figure 6 embodiment of the machine resembles that of Figure 1 with respect to the provision of the constriction plate, the manner of coarse fraction discharge through a receiving chamber, and the manner of size fractionation control by means of clear water superelevation control. But a difference lies in the manner of supplying pulsating effects to the coarse fraction bottom zone of the pool, namely by means of bodily reciprocating or vibrating the constriction plate in a vertical direction.

This machine then is represented by a tank structure for instance round or square in cross section, comprising an outer wall structure 128 having a conical or hopper-shaped bottom portion 129, an inner wall structure 130 which is upwardly and downwardly open-ended and has fixed relationship with respect to the surrounding outer wall structure 128; and a water supply chamber 131 disposed substantially within and surrounded by the hopper-shaped bottom portion 129, and comprising a horizontal top plate in the form of a constriction plate 132, a vertical wall portion 133, and a hopper shaped bottom portion 134. The inner wall structure 130 is fixedly connected with and supported by the outer wall structure 128 by means of a cover plate 135 defining above it an overflow launder 136 for receiving and discharging the overflowing fines fraction, and below it a receiving chamber 137 into which the coarse fraction particles will discharge. That is to say, the inner wall structure 130 together with constriction plate 132 defines a pool of pulp undergoing classification treatment while the outer tank wall structure 128 with hopper-shaped bottom 129 and cover plate 135 defines the surrounding receiving chamber 137.

In contrast with the preceding embodiments, the constriction plate 132 is not fixed to the surrounding vertical wall portion 133 of supply chamber 131, but has sealing relationship therewith while being vertically reciprocatable or vibratable with respect thereto in plunger-like fashion. Actuating means for so reciprocating the constriction plate are here shown to comprise a vertical

12

plunger rod 138 having its lower end rigidly connected to the top side of the constriction plate 132. The plunger rod 138 is vertically movable in an overhead girder structure 139 rigidly supported by the top end of the outer wall structure 128.

The plunger rod 138 is vibrated up and down by a bellcrank lever 140 having a horizontal arm 140a and a vertical arm 140b which bellcrank lever in turn is oscillated by a vibrating device 141. That is to say, the vibrating device being suspended as by a hanger element 142 is driven by a motor 143, to impart horizontal vibration to the end of the vertical arm 140b of the bellcrank lever, so that the horizontal arm 140a of the bellcrank lever together with the plunger rod 138 and the constriction plate 132 will be vibrated in a vertical direction.

The constriction plate 132 has a marginal upstanding rim portion 144 representing a submerged weir edge 145 across which coarse fraction material from the bottom zone of the pool may spill outwardly into the receiving chamber 137. That is to say, the weir edge 145 rises to have an overlap 146 with the lower edge portion 130a of the inner wall structure 130 even though spaced a distance 147 outwardly therefrom. The lower edge 130a is spaced upwardly from the constriction plate 132 a distance providing a coarse fraction discharge passage Z.

The receiving chamber 137 has a lateral upward extension 148 to provide a clear water balancing column defined by the top end of an overflow pipe 149a defining the top level K of the clear water column 149. The overflow level K is adjustable as indicated by removable rings 150 of the overflow pipe, the superelevation of level K over the pulp overflow level in the classifier pool being designated as M₁.

The introduction of feed pulp into the pool is indicated by a feed pipe 151. Discharge of coarse fraction particles from the hopper-shaped bottom 129 is indicated by a discharge pipe 129a provided with control or shut-off valve 129b. Means for introducing operating water into the supply chamber 131 comprise a supply pipe 152 penetrating the outer wall structure 128 as well as the vertical wall portion 133 of supply chamber 131. The supply pipe 152 has one branch pipe 153 providing a steady flow of operating water, and another branch pipe 154 providing a pulsating flow of operating water as by means of a pulsating device (not shown) which may be similar to the one shown and described in conjunction with the Figure 1 embodiment of the machine. These branch supply pipes 153 and 154 are shown to have hand-operated valves 155 and 156 respectively for shut-off or control.

The structures 133 and 134 constituting the water supply chamber is fixedly supported upon the outer wall structure 128 as is indicated by brackets 157. A so-called hutch discharge pipe 158 provided with shut-off valve 159 leads from the lowest point of supply chamber 131 through the hopper-shaped bottom 129 of the outer tank structure in sealing relationship therewith, the valve 159 being operable manually for periodically withdrawing any fine particles that may have escaped downwardly through the constriction plate into the supply chamber 131.

In the operation of the machine according to the Figure 6 embodiment, the rate of upflow water from the supply chamber 131 is such as to maintain in the classifier pool classification zones substantially similar to those described in conjunction with the preceding embodiments of the machine. That is to say, there is maintained in the pool a bottom zone "s" of coarse fraction particles for underflow discharge, a top zone "u" of fines to overflow into launder 136, and an intermediate zone "t" containing a mixture of particle sizes in teeter condition.

The coarse particles in the bottom zone are maintained in a state of fluidity by the up and down vibration of the constriction plate 132 sufficient to cause these coarse fraction particles to migrate outwardly towards and

through the discharge passage "Z" and over the submerged weir 145 into the receiving chamber 137. The desired point of size fractionation is attained and maintainable by adjusting the clear water overflow level K relative to the pulp level of pool P₂ in order to maintain a desired superelevation M₁ between these levels.

I claim:

1. Apparatus for the hydraulic classification treatment of pulp containing a mixture of particle sizes ranging from fine to coarse to effect the separation of the mixture into a fraction of fines and a fraction of coarse particle sizes, defined as undersize and oversize particles, respectively, which apparatus comprises a tank structure to hold a classifying pool defined by a horizontal bottom and walls presenting overflow means for discharging the fines fraction from the top of the pool, controllable water supply means providing a flow of operating water for said pool for emitting such operating water at a substantially uniform rate distributively in a manner whereby the water in effect rises in substantially uniform distribution from the bottom of the pool, and whereby in turn there are formed and maintained in said pool horizontal classification zones comprising substantially a lower zone of oversize particles adapted to be discharged through an outlet at the bottom, a fines zone of undersize particles adapted to discharge from the top, and an intermediate zone containing a mixture of oversize and undersize particles in teeter condition, controllable discharge means for the oversize particles, and actuating means responsive to the density of said pool for automatically controlling said discharge means in response to density changes in said pool to automatically maintain a desired fractionation between the oversize and undersize discharging from said pool; characterized by the addition of a flow control device providing rhythmic interrupted flow of water to superimpose upon said flow of operating water for inducing oversize solids in the lower zone to migrate over the tank bottom to said discharge.

2. Apparatus according to claim 1 with the addition of mechanical pulsating means for further superimposing straight pulsations upon said rhythmically interrupted auxiliary water said pulsating means having an effective reciprocatory member for automatically increasing and decreasing a confined body of water communicating with said flow of operating water.

3. Apparatus according to claim 1, in which said horizontal bottom is in the nature of a false bottom constriction plate, and the water supply means comprise a supply chamber defined by said constriction plate and by a solid bottom structure underneath said constriction plate.

4. Apparatus according to claim 1, in which said tank structure comprises an outer wall structure having a solid bottom, an inner wall structure surrounded by said outer wall structure and presenting free horizontal bottom edges, a horizontal false bottom member in the nature of a constriction plate spaced downwardly from said free horizontal bottom edges to provide outward passage for the coarse fraction particles, an upstanding discharge weir provided edgewise upon and along said bottom member and spaced outwardly from said passage in order that coarse fraction particles in said pool migrating to said passage may spill across said weir into a receiving chamber defined below, said inner wall structure together with said bottom member defining the space of the classifier pool and having fixed relationship with respect to the surrounding tank structure, and top cover means rigidly interconnecting said inner and said outer wall structure, whereby both said wall structures constitute between them said receiving chamber, and in which said discharge control means comprise a clear water column communicating with said receiving chamber to provide hydraulic balance relative to the pulp column in said pool, and means for maintaining said balance in a manner to attain said desired cut; and in which said water sup-

5

ply means comprise a supply chamber defined by said constriction plate, and by a solid bottom structure underneath said constriction plate, said chamber having a water supply conduit leading through said outer wall structure.

5. Apparatus according to claim 1, in which said horizontal bottom of the tank structure is in the nature of a false bottom constriction plate, the water supply means comprise a supply chamber defined by said constriction plate and by a solid bottom marginally connected therewith, and said underflow discharge means comprise controllable spigot valve means leading from the bottom strata of said pool.

6. Apparatus according to claim 1 in which said horizontal bottom of the tank structure is in the form of a solid plate, said underflow discharge means comprise a controllable spigot valve means leading directly from the bottom strata of said pool, and said water supply means comprise conduit means extending downwardly into said pool and having jet emitting portions adjacent to and spaced from said bottom for emitting jets of water downwardly at an angle relative to said solid bottom.

7. Apparatus according to claim 1, in which said tank structure comprises an outer wall structure having a solid bottom, an inner wall structure surrounded by said outer wall structure and presenting free horizontal bottom edges, a horizontal false bottom member in the nature of a constriction plate spaced downwardly from said free horizontal bottom edges to provide outward passage for the coarse fraction particles, an upstanding discharge weir provided edgewise upon and along said bottom member and spaced outwardly from said passage in order that coarse fraction particles in said pool migrating to said passage may spill across said weir into a receiving chamber defined below, said inner wall structure together with said bottom member defining the space of the classifier pool and having fixed relationship with respect to the surrounding tank structure, and top cover means rigidly interconnecting said inner and said outer wall structure, whereby both said wall structures constitute between them said receiving chamber, in which said discharge control means comprise a clear column communicating with said receiving chamber to provide hydraulic balance relative to the pulp column in said pool, and means for maintaining said balance in a manner to attain said desired cut; and in which said water supply means comprise a supply chamber defined by said constriction plate and by a solid bottom member underneath said constriction plate, said chamber having a water supply conduit leading through said outer wall structure; and in which said pulsation means comprise said constriction plate, means for movably mounting said constriction plate in substantially sealing relationship to said solid bottom to perform up and down vibratory movement, and drive means for imparting such vibratory movement.

8. Apparatus for the hydraulic classification treatment of pulp containing a mixture of particle sizes ranging from fine to coarse to effect size separation of the mixture into a fraction of fines and a fraction of coarse particle sizes defined as undersize and oversize particles respectively, which apparatus comprises a tank structure for holding a classifying pool defined by a horizontal bottom and walls having overflow means for discharging the fines fraction from the top of the pool, controllable water supply means providing a flow of operating water for said pool emitting such operating water at a substantially uniform rate distributively in a manner whereby the water in effect rises in substantially uniform distribution from the bottom of the pool, and whereby in turn there are formed and maintained in said pool horizontal classification zones comprising substantially a sands zone of oversize particles adapted to be discharged through an outlet at the bottom; a fines zone of undersize particles adapted to discharge from the top, and an

70

75

intermediate teeter zone containing a mixture of oversize and undersize particles, controllable discharge means for the oversize particles and actuating means responsive to the density of said teeter zone for automatically controlling said discharge means in response to density changes in said bed and to be automatically maintaining a desired fraction between the oversize and undersize discharging from said pool, characterized by the addition of a flow control device providing rhythmic interrupted flow of water superimposed upon the flow of said operating water and of mechanical pulsation means for superimposing straight pulsation upon said rhythmic interrupted flow, said pulsation means having an effective reciprocating member for automatically increasing and decreasing a confined body of water communicating with 15 said flow of operating water.

9. A method for the hydraulic classification treatment of a pulp containing a mixture of particle sizes to effect a size separation of the mixture into a fine fraction and a coarse fraction, comprising the steps of supplying said pulp to a confined zone while removing a fine solids fraction from the top thereof and controllably removing a coarse solids fraction from the bottom thereof, supplying a first flow of liquid to said zone at a uniform rate and distributed in a manner whereby said liquid rises through said zone in substantially uniform distribution, and flowing additional liquid in rhythmic interrupted flow and substantially uniform distribution upwardly through said zone.

10. Method according to claim 9 wherein pulsations developed by said additional liquid are superimposed on said first flow of liquid by introducing said additional liquid into said first flow of liquid prior to introduction into said zone.

11. Method according to claim 9 wherein additional distinct pulsations are continually applied to said zone.

12. Method according to claim 9 wherein a second clear liquid zone is established and maintained in communication with the bottom of said confined zone.

13. Apparatus for the hydraulic classification treatment of pulp containing a mixture of particle sizes

5 10 15

ranging from fine to coarse to effect the separation of said mixture into a fine fraction and a coarse fraction comprising a tank structure adapted to hold a classifying pool, means for discharging the fines fraction from the top of said pool, controllable water supply means providing a first flow of operating water for said pool at a substantially uniform rate and uniformly distributed from the bottom of said pool whereby there are formed and maintained in said pool horizontal classification zones comprising a lower zone of oversize particles to be discharged from a bottom outlet of said pool, a fines zone of undersize particles to be discharged from the top, an intermediate zone containing a mixture of coarse and fine particles in teeter condition, controllable discharge means for the oversize particles, and a second liquid supply means enabling a rhythmic interrupted flow of liquid rising in substantially uniform distribution through said pool whereby said coarse oversize particles are induced to migrate to said bottom outlet.

14. The apparatus according to claim 13 wherein said second supply means superimposes said rhythmic interrupted flow of water upon said first flow.

15. The apparatus according to claim 13 with the addition of mechanical pulsating means imposing additional distinct pulsations to said pool.

16. The apparatus according to claim 14 with the addition of mechanical pulsating means imposing additional distinct pulsations to said pool.
